UNITED STATES PATENT OFFICE.

MAURICE W. SMITH, OF LONDON, ENGLAND.

TYPE MAKING AND COMPOSING MACHINE.

SPECIFICATION forming part of Letters Patent No. 644,835, dated March 6, 1900.

Application filed August 6, 1898. Serial No. 687,953. (No model.)

To all whom it may concern:

Be it known that I, MAURICE WILLIAM SMITH, a citizen of the United States of America, and a resident of 74 St. Julian's Farm road, West Norwood, London, in the county of Surrey, England, have invented certain new and useful Improvements in Type Making and Composing Machines, of which the following is a specification.

10 This invention relates to that class of type-setting machines known as "monotype-machines"—that is to say, machines in which each individual type is separately made and subsequently transferred and set up or composed in a justified line.

15 My invention comprises a novel arrangement of dies and die-levers and a positive method of bringing all the dies to a common centering-point at the mold-wheel with absolute accuracy. The action of this machine is further improved by the peculiar construction of the mold-wheel in such a manner as to allow of automatically adjusting the widths of type. These and other objects and advantages will be revealed by the following description, which will enable persons skilled in the art to fully understand the nature of the invention.

20 The mechanism forming the well-known "monotype-machine" is very complicated and costly, necessitating, as it does, the employment of two separate machines—viz., one for producing the perforated strips of paper, which are an essential part of the manufacture, and the other for making the type.

25 According to my improvements I only require and employ a single machine, and I dispense entirely with the preparation and use of the perforated record-strips above mentioned. Further, by a simple manual operation of a button or the like I am enabled to bring any die or matrix to the common centering-point in the mold-wheel for producing cast type.

30 Referring to the accompanying drawings, Figure 1 is a sectional elevation of the improved mechanism, showing the mold-wheel and means for operating the same, as well as the die-operating mechanism. Fig. 2 is a diagram in plan, partly broken away, of the lever or operating mechanism. Fig. 3 is a plan, drawn to a larger scale, of the mold-wheel.

Fig. 4 is a plan of the means for actuating the mold-wheel; and Fig. 5 is a view of one section of the mold-wheel, showing the construction thereof. Figs. 6 to 9, inclusive, are details hereinafter referred to. Fig. 10 is an enlarged view showing the details of the mold-wheel.

35 In all the figures like letters of reference denote like parts of the mechanism.

In carrying my invention into practice I dispose a number of levers *a* in a semicircular frame *A* of a form somewhat resembling a well-known type-writing machine. These 40 levers *a*, as may be seen from Fig. 2, are arranged radially from the center of one circle, such center being the point at which the type is cast. In order to provide for a larger number of levers *a* within a limited space, I arrange the said levers to form superposed groups, as shown in Fig. 1, each group being disposed radially with the common center *b*. Each lever *a* is provided at its inner end with a die *c*, which is preferably made of copper and which may either be permanently fixed to the end of the lever or be capable of a slight motion in the end thereof. The said levers *a* are by preference adapted to be moved endwise when required to bring the dies into the centering-point *b*; but of course any other method may be adopted for the purpose. For instance, the movement of the dies may be effected by a jointed-lever arrangement, after the manner of a "Remington" or other type-writing machine. The sliding motion of the levers *a* is obtained through the intervention of elbow-levers *d*, each pivoted by its apex *d'* to a separate bracket *e*, rigidly secured to the frame *A*. To this end the long arms of these elbow-levers are connected by a pin-and-slot joint to the outer ends of the die-levers *a*, and the short arms also by a pin-and-slot joint to vertical rods *f*, suitably guided in the frame *A* and provided with buttons or touch-pieces *f'*. In all cases all the levers *a*, with their dies *c*, when not in use are withdrawn from the centering-point by the action of a spring, such as *g*, on the rods *f*. The buttons *f'* are conveniently grouped together 50 upon a keyboard such as is used in connection with pianos or with type-writing machines, and they are arranged in such a manner that an operator can with the greatest

55 60 65 70 75 80 85 90 95 100

105

ease, precision, and rapidity, by operating any one of such keys or buttons, cause the corresponding die-lever to advance and its die to instantly assume a position suitably adjacent to the centering-point *b*. I have shown in Fig. 1 means for providing vertical motion to the dies where such dies are rigidly carried at the ends of their levers. The means consist of springs *a'*, secured by one end to the frame *A* and pressing by their free end against the levers *a*, so as to keep these latter normally in contact with the upper side of a guide-slot *A'*, sufficiently elongated to allow of the slight depression necessary for the dies.

In combination with the above lever mechanism I employ a type-making mold or wheel *h*, having an intermittent rotary movement imparted to it and moving across the path of the centering-point *b*. This wheel is provided with a number of holes *h*⁰, forming molds so arranged as to be alternately placed in a position to receive the die, which is pressed down onto the mold by the action of a punch or plunger *i*, situated above the centering-point and in proximity to the advanced die. This punch or plunger *i* receives a downward motion at the time required by the action of a cam-and-lever mechanism, as indicated in Fig. 1, or by any other means usually adopted for that purpose.

The mold-wheel *h* is composed of four identical sections, one of which is shown in Fig. 5. These sections are secured together by top and bottom plates *h'* and *h*², respectively, fitted with screws, as shown in Fig. 3, and the wheel is firmly connected to a sleeve *j*, keyed on a vertical shaft *k*, carried in a bracket *A'*, which latter may be cast in one with the frame *A*. The sleeve *j* is advantageously of cylindrical form and has a square portion *j'*, forming shoulders to receive the wheel *h*. The sleeve *j* is further provided with longitudinal grooves *j*², of which there are as many as there are mold-holes in the wheel *h*. In the drawings I have shown, by way of example, four mold-holes *h*⁰ and a sleeve having four grooves *j*². In each of these grooves I arrange a wedge-shaped sliding piece *j*³, provided with means for adjusting its position and also with a spring *l* for returning the wedge *j*³ to its lowered position. This is effected by attaching the spring by one extremity to a hook *j*⁴, provided on the said wedges, and by its other extremity to a similar hook *j*⁵ on the lower portion of the sleeve *j*. In the upper end of the wedge *j*³ is formed a slot *j*⁶, adapted to engage with a collar *m'* of a lifting-rod *m*, suitably guided in the bracket *A'* and adapted to be placed in the passage of the wedges *j*³, so as to cause its collar *m'* to enter the slot *j*⁶ as each of them in succession is brought into the position adjacent to the centering-point. The required motion for the rod *m* is obtained by means of a lever *n*, having a forked or slotted front end *n'*, engaging with a pin *m*² on the rod *m*. This lever is pivoted at *n*² to a bracket

o, firmly secured to the frame *A*, and its rear end is acted upon by a vertical semicircular plate *p*. This latter is provided with vertical guide-bars *q* and carries radially-arranged pins *q'*, which are placed in such positions as to be acted upon by pins *f*², provided on the rods *f* at the time of these latter being depressed. The action will be easily understood by a glance at Fig. 1.

The four sections of the wheel *h* when placed together form a square *h*³ at the center of the wheel of such a size as to fit the square portion *j'* of the sleeve *j*. Furthermore, these sections are arranged to form slots or channels *h*⁴ between them, and they are covered at top and bottom by the plates *h'* and *h*², respectively, and serve as guides to horizontal slides *r*, which normally close and limit the size of the type or mold holes *h*⁰. The slides *r* are cut to form an incline *r'*, which is in contact with the wedges *j*³, and as these latter are normally kept in their lowest position by the pull of the springs *l* the slides *r* are forced forward and close the holes *h*⁰. If, however, one of the wedges is raised by the action of the rod *m*, the corresponding slide *r* is moved rearward against the wedge by the following means: Each slide has an extension *r*² upon one side, which is located in a recess *h*⁵ in the wheel *h*, such recess being sufficiently extended to allow of the extension *r*² to move the full stroke of its slide and to receive a spring *s*, secured to, say, the bottom plate *h*² with tendency to move the slide rearward. It is obvious that by this arrangement the position of the slide *r*, and consequently the opening or size of the hole *h*⁰, is regulated by the wedge *j*³, which itself is adjusted as to position by the keys *f* through the intervention of the rod *m*, lever *n*, and its operating mechanism, as hereinbefore described.

The mold-wheel *h* receives its intermittent rotary motion through the movement of a disk or wheel *t*, keyed on the shaft *k* and provided with pins *t'*, equally divided and corresponding in number to the mold-holes *h*⁰. This disk is rotated for a part of a revolution by means of a push-rod *u*, provided with a spring-controlled pivoted arm *u'*, having a triangular projection *u*². The rod *u* is suitably guided in the brackets *A'* and is moved endwise by means of an eccentric on the cam-shaft *v* and by its projection *u*² presses against one of the pins *t'*, so causing the disk to revolve. At the rearward motion of the rod *u* the inclined face of the projection *u*² slips over the next pin *t'* against the pressure of the spring *u*³ of the pivoted arm *u'*, and the spring thereupon keeps it in position for the next forward stroke. After each stroke the disk *t*, and consequently the mold-wheel, is kept stationary in the exact position required by a locking bar or bolt *x*, suitably operated by an eccentric on the shaft *v* and adapted to enter notches *t*², provided in the wheel *t*. The locking-bar *x* is withdrawn previously to the commencement of the forward stroke of

the push-bar u . If desired, the positive action of the eccentric in connection with the locking-bar, as above described, may be replaced by spring action, whereby the said lever is constantly kept in contact with the peripheral surface of the disk t . The notches t^2 in the disk would in this case require to be of concave or semicircular form and the head x' of the locking-bar x to be rounded, as shown, so as to enable it to automatically enter and retire from the notches t^2 .

The wheel h is held stationary for sufficient time to allow of manufacturing the type, which latter at the next rotary motion of the wheel is vertically ejected from the mold-hole h^0 by means ordinarily employed for this purpose and is dropped into a chute or conduit which serves to guide it into the galley or composing-box in which the justified line is composed. The mechanism and the action in connection with the ejecting and composing of the type are well known to persons acquainted with the art and form no part of my invention.

Having now described my invention, what I claim as new, and desire to secure by Letters Patent, is—

1. In combination in a type making and composing machine, a mold-wheel in which the type are formed one at a time, dies adapted to be moved radially to and from position over the mold in the mold-wheel, key mechanism for operating the radially-movable dies, means for giving an intermittent movement to the mold-wheel, and means operated independently of the key mechanism for forcing the dies into the molds, substantially as described.

2. In combination, the mold-wheel with means for giving a step-by-step movement thereto, a series of radially-arranged die-bars with key mechanism for sliding them along right lines toward and from the mold-wheel, and means for forcing the dies into the molds, said means being operated independently of the key mechanism, substantially as described.

3. In a type making and composing machine having a semicircular frame with die-levers adapted to advance any one die to a common centering-point, an intermittently-rotated mold-wheel having a number of holes or type-molds adapted to be placed in succession in the centering-point of the dies, substantially as set forth.

4. In a type making and composing machine the combination of a mold-wheel with means for giving a step-by-step movement

thereto, a series of radially-arranged dies and die-bars with key mechanism for sliding said bars along right lines toward and from the mold-wheel, means for allowing of a slight vertical motion for the dies consisting of leaf-springs attached to the dies, and means for forcing the dies into the molds, said means being operated independently of the key mechanism, substantially as described.

5. In a type making and composing machine, a mold-wheel composed of four sections and top and bottom plates fitted with screws for securing these sections together, and having channels or passages fitted with slides for adjusting the size of the type-molds, substantially as set forth.

6. In a type making and composing machine, a mold-wheel composed of four sections and top and bottom plates fitted with screws for securing these sections together and having slides moving endwise in channels or passages formed between the sections of the wheel in combination with vertical wedges for adjusting the said slides, substantially as set forth.

7. In a type making and composing machine, a horizontally-arranged mold-wheel having a number of type-molds and composed of four equal sections secured together by a top and bottom plate, and fitting onto the square portions of a sleeve keyed on a vertical shaft, substantially as set forth.

8. In a type making and composing machine the combination with a mold-wheel formed of four sections and having a number of mold-holes and slides for adjusting the size of such mold-holes, vertically-arranged wedges for operating the slides, of means for operating the said wedges successively through the action of the keys or buttons upon the keyboard substantially as set forth.

9. In a type making and composing machine the combination with a mold-wheel formed of four sections and having a number of mold-holes and slides for adjusting the size of such mold-holes, and wedges for operating these slides, of the means for intermittently rotating and locking the wheel in position, substantially as and for the purpose set forth.

In witness whereof I have hereunto signed my name in the presence of two subscribing witnesses.

MAURICE W. SMITH.
